United States Patent Office

Des. 190,657

Patented June 20, 1961

190,657

AMUSEMENT DEVICE

Frank W. Ferrin, 8673 Valley Flores Drive,
Canoga Park, Calif.

Filed Feb. 17, 1961, Ser. No. 64,128

Term of patent 14 years

(Cl. D34—5)

FIG. 1 is a side perspective view showing my new design for an amusement device, and

FIG. 2 is a front perspective view thereof.

The dominant features of the design reside in the portions shown in full line.

I claim:

The ornamental design for an amusement device, as shown and described.
